UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

PERMISSIVE AUTOMATIC TRAIN-CONTROL SYSTEM

Application filed November 27, 1925. Serial No. 71,751.

This invention relates to automatic train control and more particularly concerns an automatic train control system of the well known continuous inductive type.

Modern systems of automatic train control have in general been designed to safeguard and facilitate train operation and to provide an additional safety control over that afforded by the engineer in his observation of the wayside signals and his control of the train in accordance with the indications thereof. It is therefore thought advisable to arrange the automatic train control system in such a manner that the proper observance of wayside signals by the engineer is encouraged, and this has been accomplished in many systems by providing a system which incorporates the feature of acknowledgement; that is, a system in which the engineer may, by the performance of some suitable acknowledging act when a signal presenting an unfavorable aspect is encountered, avoid an automatic brake application, a restrictive speed limit or other penalty or annoyance.

In many of the systems incorporating the acknowledging feature described above, it has been found that although the engineer is required to acknowledge the first unfavorable signal which he encounters, the acknowledged condition of the apparatus persists, and if successive unfavorable signals are encountered, no further acknowledgement is required. In other words, in these systems, the engineer is not encouraged or required to remain alert and vigilant in his observation of successive danger or caution signals provided he has properly acknowledged the first of these unfavorable signals.

With the above and other considerations in mind, it is proposed in accordance with the present invention to provide an automatic train control system of the continuous inductive type in which the engineer may avoid an automatic brake application by properly acknowledging each unfavorable signal indication, and in which the acknowledgement of successive unfavorable signal indications is required to continue the avoidance of an automatic brake application.

More specifically it is proposed to provide a system in which a stick relay is energized if an unfavorable signal is properly acknowledged and in which this stick relay is maintained energized at successive unfavorable signals only if the acknowledging act is repeated at such unfavorable signals. 55

Other specific objects, advantages and characteristic features of the invention will become apparent as the description thereof 60 progresses.

In describing the invention in detail, reference will be made to the accompanying drawing in which a single figure representing the car-carried and trackway apparatus of a system of train control embodying the present invention in a diagrammatic and conventional manner has been shown. 65

Referring now more particularly to the trackway apparatus shown in the drawings, 70 the track rails 1 have been shown divided into the usual blocks by the insulating joints 2, the block I and the ends of the two adjacent blocks H and J having been shown. As the devices and apparatus used in connection with the successive blocks are identical, like reference characters having distinctive exponents are used to designate the corresponding elements in the successive blocks. 75

The usual track relays 3 have been shown 80 connected across the track rails at the entrance ends of the blocks. The track circuit current for operating these relays is supplied by the batteries 4 connected across the track rails at the exit ends of the blocks in series 85 with the secondary winding of the transformer 5. The usual track phase train control current is supplied to the two track rails of each block in series through the transformer 5, the contact fingers 6 and 7 and front 90 contacts of the track relay 3 and the transformer 8 connected to the transmission line 9, this circuit being obvious from the drawings. It is obvious, that if a train is located in a given block, the track circuit current is 95 shunted from the track rails by the wheels and axles of such train and the track relay 3 at the entrance end of this block is de-energized. The de-energization of the track relay at the entrance end of a given block causes 100

the track phase train control current to be cut off from the track rails at the track relay contact fingers 6 and 7, so that with a train located in a given block no train control current flows in the track rails of that portion of the given block in the rear of the train or in the track rails of the first block in the rear.

Wayside signals of some suitable type are preferably employed in connection with the train control system of the present invention, and for the purpose of illustration, semaphore wayside signals of the well known type have been illustrated at Z. Since the controlling and operating devices and circuits for these wayside signals are well known to those skilled in the art and form no part of the present invention, a showing of these devices and circuits has been omitted, it being understood that a signal at the entrance end of an occupied block or at the entrance end of the first block to the rear of an occupied block is automatically moved to a position to give a suitable unfavorable indication.

Acknowledging loops 10 are provided near the exit end of each block. These acknowledging loops may take any suitable form, and as illustrated, comprise wires which are located in close proximity to the track rails and which extend for a suitable distance, preferably 200 feet or more, from the exit end of the block. These acknowledging loops are continuously supplied with alternating current of train control frequency through the transformers 11, connected to the transmission line 9, and thus present a permanent magnetic field in close proximity to the track rails near the exit end of each block. It should be understood that the track rails themselves might be provided with insulated sections near the exit end of each block, and that these sections might be permanently energized to form acknowledging loops. The function and operation of the acknowledging loops will be explained in connection with the operation of the system as a whole.

Referring now to the car-carried apparatus of the present invention, a railway vehicle has been conveniently represented by the wheels and axles 12 in the block H, the normal direction of traffic being indicated by the arrow. Inductive receiving coils 13, which may or may not be provided with laminated iron cores, are located on the vehicle in front of the leading axle thereof and in inductive relation to the track rails 1. These receiving coils 13 are so connected that voltages induced therein by alternating currents flowing in opposite directions in the two track rails are cumulative. The receiving coils 13 are connected, through a circuit which is preferably tuned to resonance at the frequency of the train control current by the condenser 14, to a suitable amplifier A, preferably of the audion tube type.

The output circuit of the amplifier A is

connected to a main car relay MR. As shown, this relay is of the simple two-position A. C. type, but it should be clearly understood that a polyphase relay might be provided, its local phase winding being excited in any suitable manner. The vehicle-carried apparatus also includes a secondary relay S, an acknowledging relay Ack and a valve relay VR, all of these relays being of a direct current type. The secondary relay S is made slow acting by some suitable means such as the provision of a copper sleeve around its core to sustain the flux therein, the purpose of this slow-acting feature being hereinafter described. The acknowledging relay Ack is provided with two separate windings, one winding being connected in a pick-up circuit and the other in a stick circuit as hereinafter described.

Two manually operable circuit controlling devices are provided in connection with the car-carried apparatus, these controlling devices being designated as the acknowledging contactor AC and the reset contactor RC. The acknowledging contactor AC is provided with two contact fingers 16 and 17, the contact finger 16 being normally opened and the finger 17 being normally closed. The contact finger 17 is so arranged that it does not disengage its front contact 18 until a given period of time after the finger 16 has engaged its back contact. Any suitable means may be provided for accomplishing this result, and in the drawings a simple flexible contact finger and dash pot arrangement has been shown. The acknowledging contactor AC is located in some convenient point, preferably in the locomotive cab within easy access of the engineer. The reset contactor RC is provided with a contact finger 19 which normally engages its front contact 20, and a contact finger 21 which is normally disengaged from its stationary back contact 22. This reset contactor RC is located at some point on the locomotive where it may be operated only from the ground, so that the locomotive must be brought to a stop before its operation can be effected.

Cab signals of any suitable type may or may not be provided in connection with the present invention. For the purpose of illustration, the cab signals G and R have been shown, it being understood that these signals comprise suitable lamps or other visible indicating devices located in the vehicle cab within view of the engineer.

The vehicle brakes may be automatically controlled in any one of a number of well known ways and by means of any suitable arrangement of devices. As the initiation of an automatic brake application is usually effected by some type of electro-pneumatic valve, the electro-pneumatic valve EPV has been illustrated, it being assumed that the de-energization of the windings of this valve initiates a restrictive automatic brake appli-

cation, eventually bringing the vehicle to a stop.

Operation

5 The various circuits and devices have been shown in their normal condition, that is, with all circuits properly energized and the vehicle proceeding under clear traffic conditions. In order to simplify the wiring diagram, the letters B and C have been used to denote the positive and negative terminals of a suitable source of electrical energy, such as a storage battery or a turbo-generator.

With a vehicle traveling in a clear block, 15 voltages of train control frequency are induced in the receiving coils 13, amplified by the amplifier A and act to energize the main car relay MR. With the main car relay energized, the secondary relay S is energized 20 through the contact finger 23 of the main relay MR and a circuit which is obvious from the drawings. The valve relay VR is energized through the contact finger 24 and front contact of the main relay MR, wires 25 and 26, as clearly shown. With the valve relay VR energized and the reset and acknowledging contactors in their normal positions, an energizing circuit for the electro-pneumatic valve EPV is completed which circuit may be 30 traced as follows:—from the battery terminal B, contact finger 19 and front contact 20 of the reset contactor RC, wire 27, contact finger 17 and front contact 18 of the acknowledging contactor AC, wire 28, contact finger 29 and 35 front contact of the valve relay VR, wire 30 and the winding of the electro-pneumatic valve EPV to the battery terminal C. With the electro-pneumatic valve EPV energized, the train under consideration may 40 proceed in the clear block without automatic restriction, the engineer being informed of the fact that traffic conditions are clear by the indication of the clear cab signal G which is energized through the contact finger 31 and front contact of the main relay MR and a circuit which is obvious from the drawings.

Assume now that the train approaches the entrance end of a block in which unfavorable 50 traffic conditions exist, this block being the first block in the rear of an occupied or danger block and being hereinafter designated as a caution block. If the engineer is alert and properly observes and recognizes 55 the indication of the wayside signal at the entrance to the caution block, he operates the acknowledging contactor AC just before the locomotive enters the caution block and releases this acknowledging contactor shortly 60 after this block is entered. When the acknowledging contactor AC is depressed with the vehicle still located in the clear block and the main relay MR energized, a pick-up circuit for the acknowledging relay Ack is completed, which circuit may be traced as fol-

lows:—from the battery terminal B, contact finger 16 and stationary contact 32 of the acknowledging contactor AC, wire 33, contact finger 34 and front contact of the valve relay VR, wires 35 and 36 and the winding 70 37 of the acknowledging relay Ack to the battery terminal C. It should be observed that if the engineer is late in closing the acknowledging contactor AC so that this contactor is not closed until the vehicle has gone some little distance into the caution block, the circuit traced above can not be completed for the reason that the main relay MR will have been de-energized causing the de-energizing of the valve relay VR at the contact finger 24 75 of the main relay, and contact finger 50 of relay S, the de-energization of the valve relay VR breaking the circuit just traced at its contact finger 34 and front contact. If the acknowledging relay Ack is properly picked up as described above, it is stuck up as soon as the loop 10 in question is passed and the main relay is de-energized, through a stick circuit which may be traced as follows:—from the battery terminal B, contact finger 31 and 80 back contact of the main relay MR, wires 38, 39 and 40, contact finger 41 and front contact of the acknowledging relay Ack and wire 42 and the winding 43 of the acknowledging relay Ack to the battery terminal C. It is of course understood that the engineer must maintain the acknowledging contactor AC depressed until after de-energization of relay MR to permit the stick circuit just traced to be completed, it being remembered that the slow acting characteristic of relay S maintains relay VR up until after relay MR has assumed its deenergized position. The energization of the acknowledging relay Ack causes the valve relay VR to be energized 90 through a circuit which may be traced as follows:—from the battery terminal B, contact finger 44 and front contact of the acknowledging relay Ack, wires 45 and 46 and the winding of the valve relay VR to the battery 95 terminal C. With the valve relay VR thus energized, the electro-pneumatic valve EPV is energized through its circuit which has been traced above, and the train under consideration may proceed through the caution 100 block without automatic restriction. 115

If the engineer is not vigilant and fails to acknowledge the caution signal before the relay S has dropped away, the pick-up circuit for the acknowledging relay cannot be completed because of the de-energization of the valve relay VR as described above. This de-energization of the valve relay breaks the energizing circuit for the electro-pneumatic valve EPV, which circuit has been traced 120 above, and an automatic brake application results, bringing the train to a stop. The engineer must then dismount from the cab and operate the reset contactor RC, thus closing a pick-up circuit for the acknowledging relay 125 130

Ack, which circuit may be traced as follows:— from the battery terminal B, contact finger 31 and back contact of the main relay MR, wires 38, 39 and 47, contact finger 21 and stationary contact 22 of the reset contactor RC, wires 48 and 36 and winding 37 of the acknowledging relay *Ack* to the battery terminal C. Once energized, the acknowledging relay *Ack* is maintained energized through the stick circuit traced above, the valve relay VR is energized through the contact finger 44 and the circuit traced, the energizing circuit for the electro-pneumatic valve EPV is closed at the contact finger 29 of the valve relay VR and the engineer may then release the vehicle brakes and proceed in the caution block. It should be observed that the engineer can not defeat the operation of the automatic control by securing either the reset contactor RC or the acknowledging contactor AC in their operated positions for the reason that both of these contactors are provided with normally closed contacts which are included in the energizing circuit for the electro-pneumatic valve EPV, and if either of these contactors were maintained in the operated position, this energizing circuit would be broken and an automatic brake application would result.

Assume now that the train under consideration approaches the exit end of a caution block with the acknowledging relay properly energized by a previous acknowledgement or a reset as described above, and that the way-side signal at the entrance end to the next block is in its stop or danger position, indicating that the next block is occupied. As the train reaches the end of the caution block it encounters the acknowledging loop 10, which is constantly energized with alternating current of train control frequency as described above. If the engineer properly observes and recognizes the danger or stop signal he depresses the acknowledging contactor AC as the vehicle encounters the acknowledging loop 10. Under these conditions the main relay MR is energized in response to the current flowing in the acknowledging loop 10 and breaks the stick circuit for *Ack* at contact finger 31. Depression of AC completes the pick-up circuit for the acknowledging relay *Ack* through the contact finger 16 and stationary contact 32 of the acknowledging contactor AC, this circuit having been traced above. As the train passes into the danger or occupied block beyond the loop 10, the main relay MR is again de-energized, retracting its contact finger 31 and thus again completing the stick circuit for the acknowledging relay *Ack*, which circuit has been traced above. The train may now proceed in the danger block without automatic restriction, the vigilance of the engineer having been manifested by his proper acknowledgement of the danger signal. If successive stop

signals are encountered by the train under consideration, the acknowledging act just described must be repeated by the engineer at each successive stop signal in order to prevent the de-energization of the acknowledging relay *Ack* and a consequent automatic brake application.

If the engineer fails to acknowledge a stop signal when leaving a caution block, the brief energization of the main relay MR due to a loop 10 causes the stick circuit of the acknowledging relay *Ack* to be broken by the disengagement of the contact finger 31 and back contact of the main relay. Shortly after the vehicle has passed the loop 10, thus causing de-energization of relay MR and relay S, this de-energization together with the de-energization of the acknowledging relay, causes the valve relay VR to be de-energized, thus breaking the energizing circuit to the electro-pneumatic valve EPV at the contact finger 29 of the valve relay VR, and initiating an automatic brake application as described above.

In applying a system of continuous train control to the track rails of existing railway systems, many points are encountered at which it is impossible to maintain the continuous flow of train control current in the track rails. This condition which occurs at switch frogs, cross overs and like points, would ordinarily cause the de-energization of the main relay MR and a consequent automatic brake application. In the system of the present invention, an automatic brake application as a result of these "dead sections," as they are ordinarily called, is prevented by the operation of the secondary relay S. This relay is made slow-acting as set forth above, and when the main relay MR is de-energized, retracting its contact finger 23 and thus de-energizing the secondary relay S, this relay S does not retract its contact finger 50 for a given interval of time, in general only a few seconds, after its de-energization. The fact that the contact finger 50 of the secondary relay S remains in engagement with its front contact for a time interval after the main relay MR is de-energized insures that the valve relay VR be maintained energized while the dead section is being traversed, the contact finger 50 and front contact of the secondary relay S maintaining an alternative energizing circuit for the valve relay VR through the wires 51, 26 and 46 as clearly shown in the drawings. The time required for the secondary relay S to retract its contact finger 50 after the de-energization of the windings thereof is so arranged that the longest dead section ordinarily encountered in practice is traversed before this contact finger 50 is retracted, provided the train is proceeding at or above a given speed.

As described, the provision of the slow acting relay S, avoids automatic brake applications due to so-called "dead sections"

of track. With this relay S constructed to be slow acting, there might be thought to be a disadvantage, upon going from a caution into a danger block, since with no acknowledgment, the train could proceed beyond the end of a loop 10 a distance depending upon the speed of the train and the time constant of the relay S, before suffering an automatic brake application. However this feature, as a defect, is more apparent than real, since the time constant of slow acting relay S is so small, at most only a few seconds, that the brakes are applied a very short distance beyond the end of a loop 10, under the conditions just stated.

Furthermore the braking distance for an average train at average speed, is so great, that, to add to this braking distance a short distance due to the slow acting feature of relay S does not materially increase the distance that a train can proceed into a danger block under the conditions stated, before being brought to a stop.

Also, of course, the slow action of relay S adds a few seconds to the time during which the acknowledgment can be completed, but this can in no manner be considered a disadvantage.

It is to be realized however that under such systems as the present, after an engineer has acknowledged on entering a caution block his vigilance can be depended upon to some extent upon entering a subsequent danger block or caution block as the case may be, to avert accident due to the capability of the train to enter into the danger or caution block in question a certain distance before being brought to a stop.

From the description above given it is seen that a system of automatic train control has been provided in which acknowledgment of all unfavorable signals is enforced, and in which successive danger or caution signals must be acknowledged to prevent an automatic brake application.

As the above invention has been described in connection with a rather specific system of train control, it is to be clearly understood that certain changes, additons and modifications might be made without departing from the spirit of the invention as defined by the appended claims.

What it is desired to secure by Letters Patent is:—

1. In an automatic train control system of the type in which control influences corresponding to traffic conditions are continuously transmitted from the trackway to a moving vehicle, car-carried control apparatus comprising a normally energized device for initiating a brake application when de-energized, a stick relay having a pick-up circuit which may be manually closed only under favorable traffic conditions and for a short time after the cessation of influences

corresponding to favorable traffic conditions and having a stick circuit which is closed only when unfavorable traffic conditions are manifested on the vehicle, said stick relay acting when energized to prevent the de-energization of said brake applying device, and trackway means at spaced points for transmitting influences corresponding to favorable traffic conditions for a limited distance of vehicle travel, whereby said pick-up circuit must be manually closed at said spaced points under unfavorable traffic conditions to maintain said stick relay energized and to prevent the deenergization of said brake applying device.

2. In an automatic train control system, trackway apparatus for continuously transmitting electrical influences to vehicle receiving means under favorable traffic conditions and for cutting off said influences under unfavorable traffic conditions, car-carried apparatus comprising a normally energized brake applying device adapted to apply the vehicle brakes when de-energized, means for maintaining said brake applying device energized when said influences are being transmitted and for de-energizing said device a short time after said influences are cut off, a stick relay acting when energized to maintain said brake applying device energized while said influences are cut off, a pick-up circuit for said stick relay including a manually operable circuit closer and a contact closed only under favorable traffic conditions and for a short time after the cessation of said influences, a stick circuit for said stick relay closed only when said influences are cut off, and means at spaced points along the trackway for transmitting said influences for a limited distance of vehicle travel under all traffic conditions, whereby when a vehicle is traveling in a section of trackway where said influences are cut off, said manually operable circuit closer must be operated at said spaced points to maintain said brake applying device energized and to avoid an automatic brake application.

3. In an automatic train control system, trackway apparatus for transmitting influences to a moving vehicle continuously under favorable traffic conditions and for cutting off said influences under unfavorable traffic conditions, vehicle carried apparatus comprising a main relay energized during the transmission of said influences, a brake applying device initiated to cause an automatic brake application a short time after said main relay is de-energized, means for maintaining said brake applying device inactive comprising a stick relay, a pick-up circuit for said stick relay including a manually operable circuit controller and a contact closed only when said main relay is energized and for a short time after de-energization of said main relay, a stick circuit for said stick relay

closed only when said main relay is de-energized, means for initiating said brake applying device if said manually operable circuit controller is maintained closed for more than 5 a predetermined time interval, and trackway means at spaced points for transmitting said influences for a limited distance of vehicle travel under all traffic conditions, whereby 10 said manually operable circuit controller must be operated at each of said spaced points under unfavorable traffic conditions to prevent the initiation of said brake applying device.

4. In an automatic train control system, in 15 combination with track rails divided into blocks, trackway means for transmitting electrical influences continuously to receiving apparatus on a moving vehicle in each block under favorable traffic conditions and 20 for cutting off said influences under unfavorable traffic conditions ahead, vehicle carried apparatus comprising a main relay, energized in accordance with the transmission of said influences, a valve relay energized in accordance with the energization of said main 25 relay and which will not drop until a short time after de-energization of said main relay, a normally energized brake applying device acting when de-energized to initiate a brake 30 application and being energized through a front contact of said valve relay, a stick relay acting when energized to maintain said valve relay energized, a pick-up circuit for said stick relay including a manually operable 35 circuit closer and a front contact of said valve relay, a stick circuit for said stick relay including a back contact of said main relay, and trackway means adjacent the exit end of each 40 block for transmitting said influences for a limited distance of vehicle travel under all traffic conditions, whereby said manually operable circuit closer must be operated upon each entrance of the vehicle into the next 45 succeeding block when unfavorable traffic conditions exist in that next block.

5. In a train control system, a normally energized brake initiating device made active by de-energization, a traffic responsive device for controlling energy flow to the brake device through the intermediaries of a slow acting relay and a valve relay, an energizing circuit for the slow acting relay running through a front contact of the traffic responsive device, multiple branched energizing circuit for the valve relay with the branches running, respectively, through front contacts of the traffic responsive device and the slow acting relay, a stick relay having a front contact included in an auxiliary energizing circuit for said valve relay, and time protected manually operable acknowledging means for picking up said stick relay.

6. In a train control system, a normally energized brake initiating device made active by de-energization, a traffic responsive device

for controlling energy flow to the brake device through the intermediaries of a slow acting relay and a valve relay, an energizing circuit for the slow acting relay running through a front contact of the traffic responsive device, a multiple branched energizing circuit for the valve relay with the branches running, respectively, through front contacts of the traffic responsive device and the slow acting relay, the energizing circuit for the brake device running through a front contact of the valve relay, a stick relay having a front contact included in an auxiliary energizing circuit for said valve relay, and time protected manually operable acknowledging means for picking up said stick relay.

7. In a train control system, a normally energized brake initiating device made active by de-energization, a traffic responsive device for controlling energy flow to the brake device through the intermediaries of a slow acting relay and a valve relay, an energizing circuit for the slow acting relay running through a front contact of the traffic responsive device, and a multiple branched energizing circuit for the valve relay with the branches running, respectively, through front contacts of the traffic responsive device and the slow acting relay, the energizing circuit for the brake device running through a front contact of the valve relay, and a stick device, capable of being picked up only when the valve relay is energized and of being stuck up only when the traffic responsive device is de-energized, for energizing the valve relay through an auxiliary circuit.

8. In an automatic train control system of the continuous inductive type wherein continuously active acknowledging loops are employed near the exit end of each block for 105 enforcing acknowledgments by the engineer of his entrance into a danger block, the combination with a track divided into blocks each including the usual normally closed track circuit, means for causing the flow of alternating 110 current in such track circuit when the block next in advance thereof is unoccupied, a vehicle movable over said trackway, a main relay on said vehicle controlled in accordance with current in the track rails ahead of said vehicle, a slow acting relay controlled by said main relay, a valve relay controlled by said slow acting relay, an electro-pneumatic brake control means controlled by said valve relay, a stick relay which if energized maintains 115 said valve relay energized, said stick relay having a pickup circuit which may be closed only by the engineer if said valve relay is in its energized condition, and a stick circuit for said stick relay closed only if said main relay 120 is in its de-energized condition.

9. In an automatic train control system of the continuous inductive type wherein continuously active acknowledging loops are employed near the exit end of each block for en- 125

forcing acknowledgments by the engineer of his entrance into a danger block, the combination with means partly on the vehicle and partly along the trackway for transmitting influences from the trackway to the vehicle throughout each block under clear traffic conditions and at the exit end of each block under caution and danger traffic conditions, a main relay on said vehicle energized in response to such control influences, a slow acting relay controlled by said main relay, brake control means controlled by said slow acting relay, a stick relay, an auxiliary circuit for energizing said brake control means closed if said stick relay is energized, a pickup circuit for said stick relay including a contact only closed when said brake control means is in its normal condition, and a stick circuit for said stick relay including a contact closed only when said main relay is de-energized.

10. In an automatic train control system of the continuous inductive type wherein continuously active acknowledging loops are employed near the exit end of each block for enforcing acknowledgments by the engineer of his entrance into a danger block, the combination with means partly on the vehicle and partly along the trackway for transmitting influences from the trackway to the vehicle throughout each block under clear traffic conditions and at the exit end of each block under caution and danger traffic conditions, a main relay on said vehicle energized in response to such control influences, a slow acting relay controlled by said main relay, brake control means controlled by said slow acting relay, a stick relay, an auxiliary circuit for energizing said brake control means closed if said stick relay is energized, a pickup circuit for said stick relay including a contact only closed when said brake control means is in its normal condition, and a supplemental pickup circuit for said stick relay including a contact closed only if said main relay assumes its de-energized condition.

11. In an automatic train control system of the continuous inductive type wherein continuously active acknowledging loops are employed near the exit end of each block for enforcing acknowledgments by the engineer of his entrance into a danger block, the combination with means partly on the vehicle and partly along the trackway for transmitting influences from the trackway to the vehicle throughout each block under clear traffic conditions and at the exit end of each block under caution and danger traffic conditions, a main relay on said vehicle energized in response to such control influences, a slow acting relay controlled by said main relay, brake control means controlled by said slow acting relay, a stick relay, acknowledging means for closing a pickup circuit for said stick relay effective only if said brake control means is in its normal inactive condition, reset means for pick-

ing up said stick relay effective only if said main relay is in its de-energized condition, and means for protecting said acknowledging means and said reset means against misuse.

In testimony whereof I affix my signature. 76
